AUTOMOBILE WHEEL COVER

George A. Schmidt, Detroit, Mich., assignor to Chrysler Corporation, Highland Park, Mich., a corporation of Delaware

Application June 11, 1956, Serial No. 41,822

Term of patent 7 years

(Cl. D14—30)

Fig. 1 is a front elevational view of an automobile wheel cover, showing my new design; and

Figs. 2 and 3—3, respectively, of Fig. 1.

The dominant features of my design reside in the portions shown by means of full lines in the drawing.

I claim:

The ornamental design for an automobile wheel cover, substantially as shown and described.
